UNITED STATES PATENT OFFICE.

JAMES JOHNSON SHUTTLEWORTH, OF LAURISTON RYDE, NEW SOUTH WALES.

STOPPER AND FASTENING FOR BOTTLES, JARS, CASKS, OR OTHER VESSELS.

SPECIFICATION forming part of Letters Patent No. 636,078, dated October 31, 1899.

Application filed December 22, 1898. Serial No. 700,072. (No model.)

To all whom it may concern:

Be it known that I, JAMES JOHNSON SHUTTLEWORTH, architect, a subject of the Queen of Great Britain, residing at Lauriston Ryde, 5 near Sydney, in the British Colony of New South Wales, have invented new and useful Improved Stoppers and Fastenings for Bottles, Jars, Casks, or other Vessels, of which the following is a specification.

This invention relates to improved stoppers and fastenings for bottles, jars, casks, and other vessels which have been specially devised in order to prevent such vessels being fraudulently reused. These improved stoppers and fastenings for bottles, jars, casks, and other vessels have as their essential feature two or more wires or indestructible cords fastened during manufacture in the body of the vessel or in some object which cannot be removed from within the vessel, which wires are adapted to be knotted together over a keeper on the outside of the vessel and have their ends cut off close to the knot. When these wires are broken (or even untied) to release the keeper and enable the vessel to be opened, they are too short to be used again in retying. In addition to this essential feature it is always preferred that the keeper should have upon or under it a seal or other 30 mark of genuineness and that the irremovable object should bear the same, and it is sometimes preferred that the knot of the fastening-wires should be buried in a glass seal or in transparent cement or under a removable protector on the outside.

In order that this invention may be clearly understood, reference will now be made to the drawings herewith, which show a variety of stoppers and fastenings all having common 40 to them the essential feature of this invention before mentioned.

Figure 1 is a vertical section of a bottle-neck and stopper, showing my invention. Fig. 2 is a plan view of Fig. 1. Fig. 3 is a vertical section of a modified construction. Fig. 4 is a plan view of Fig. 3. Fig. 5 is a transverse section of the construction shown in Fig. 1.

Figs. 1, 2, and 5 show sectional elevation, plan, and horizontal section, respectively, of 50 the neck E of a bottle, showing a cork or stop-

per D, retained in place by a glass keeper B, fastened by wires A secured to lugs A' in the body of the neck E during manufacture. When the bottle is filled, the cork D is driven in, filling the neck E and bulging in the upper enlargement E'. A seal C or a disk of metal or paper, or other material bearing a brand, is placed over the cork, so that an inscription or other mark may be read from the top through the glass (transparent) keeper 60 B, which being put in place, then wires A are threaded through holes B' through it. Being drawn tight, these wires A are knotted centrally of the stopper and the ends cut off as close to the knot as possible. Said knot is 65 then buried in wax, lead, or cement or the like, but preferably glass, in undercut recess A². The mark on the seal or disk C may always be read through the stopper B, and when once this seal (or disk) is destroyed in drawing the cork it cannot again be used as a 70 guarantee of the genuineness of the contents of the bottle. Further, the wires A must be broken to remove the keeper B, so as to get at the cork D, and being once broken (or even 75 untied) they cannot be used a second time, for they would be too short for tying together again. It will be seen, therefore, that once the keeper B is removed, though the bottle may be utilized for other purposes, yet it cannot again be used with a guarantee that its 80 contents are genuine.

Figs. 3 and 4 are section and plan, respectively, of a modification of the stopper and fastening shown in Figs. 1, 2, and 5, where 85 all the parts are identical and marked with the same letters of reference; but the wires A are not fixed to lugs A', but simply buried in the body of the neck, and instead of being threaded through holes in the keeper B pass 90 up in nicks (marked with the same letter, B') in its edge.

Having now particularly described and ascertained the nature of my said invention and in what manner the same is to be performed, 95 I declare that what I claim is—

1. The combination with a bottle having wires sealed in the glass of its neck, of a cork inserted in said neck, a disk resting upon said cork, a keeper over which the wires pass and 100

are united, and a seal over the ends of the wires located in a recess in the top face of the keeper, substantially as specified.

2. The combination with a bottle, of a cork 5 therein, a disk to receive an inscription or other mark, a keeper having a portion extending within the neck of the bottle and a portion resting upon the outer end thereof with a space between the inner end of the 10 keeper and the disk, and an undercut recess in the outer face of the said keeper, and wires

sealed in the glass of the neck and having their ends passed over the keeper and united over the said recess, and a seal for holding the ends of the wires together and in said recess, 15 all substantially as specified.

Dated this 14th day of November, 1898.

JAMES JOHNSON SHUTTLEWORTH.
